UNITED STATES PATENT OFFICE.

WILLIAM A. HULBERT AND MILAN H. HULBERT, OF NEW YORK, N. Y.

DESIGN FOR A BICYCLE-SADDLE.

SPECIFICATION forming part of Design No. 25,837, dated March 31, 1896.

Application filed February 28, 1896. Serial No. 581,210. Term of patent 7 years.

To all whom it may concern:

Be it known that we, WILLIAM A. HULBERT and MILAN H. HULBERT, citizens of the United States, residing at New York, in the county and State of New York, have invented and produced a new and original Design for Bicycle-Saddles, of which the following is a specification, reference being had to the accompanying drawings, showing a part thereof.

Figure 1 is a plan view of a saddle, showing our design; and Fig. 2 is a cross-sectional view on line x x of Fig. 1, these two views being deemed necessary to fully illustrate said design.

15 The leading feature of our design consists, in brief, of an outline of general pelecoidal shape having a centrally-disposed rectangular opening. Upon the said rectangular field are displayed lines extending transversely and longitudinally of the saddle, said lines being interwoven, as illustrated.

The letter a indicates that portion of our design corresponding to the rear end of the saddle, the same being semi-oval, and from the extreme ends of said semi-oval portion inwardly-curved lines b b extend forward, gradually approaching each other, being finally connected by a substantially semicircular line c at the pommel end of the saddle design. 25

The side walls of the said design extend upward and curve inward, as in Fig. 2. 30

What we claim is—

The design for a bicycle-saddle substantially as herein shown and described.

WM. A. HULBERT.
MILAN H. HULBERT.
